DESIGN FOR A BOTTLE

Charles P. Englehardt, New York, N. Y., assignor to Oldetyme Distillers, Inc., New York, N. Y., a corporation of New Jersey

Application April 20, 1936, Serial No. 62,210

Term of patent 14 years

To all whom it may concern:

Be it known that I, Charles P. Englehardt, a citizen of the United States, residing at New York, in the county of Kings and State of New York, have invented a new, original, and ornamental Design for a Bottle, of which the following is a specification, reference being had to the accompanying drawing, forming part thereof.

I claim:

The ornamental design for a bottle substantially as shown.

CHARLES P. ENGLEBARDT.
